UNITED STATES PATENT OFFICE.

CHARLES E. SARGENT, OF ROCK ISLAND, ILLINOIS.

POPPET-VALVE ROTATOR.

Application filed July 15, 1922. Serial No. 575,355.

To all whom it may concern:

Be it known that I, CHARLES E. SARGENT, a citizen of the United States, residing at Rock Island, in the county of Rock Island and State of Illinois, have invented a new and useful Poppet-Valve Rotator, of which the following is a specification.

It is the object of my invention to provide an efficient and reliable device for rotating poppet valves of internal combustion engines on their seats, without twisting or otherwise distorting the valve-seating springs; and to do so by a structure which is simple and inexpensive, and can readily and cheaply be installed on existing engines.

It has long been recognized that if poppet valves of internal combustion engines are rotated on their seats as they are opened and closed, the valves will remain tight for a much longer time, sometimes for indefinite periods, and will operate more satisfactorily, and that the operation of grinding the valves in their seats will be required much less frequently, and in some cases not at all. Devices for obtaining this rotation of poppet valves have been proposed, and to some extent have been used; but they have usually involved rather complicated constructions, and frequently have involved a distortion of the valve-seating springs. By my present invention, I avoid these difficulties.

The accompanying drawing illustrates my invention: Fig. 1 is a vertical central section through a pair of poppet valves of an internal combustion engine, equipped with my improved valve-rotating device; Fig. 2 is a bottom plan of the arrangement shown in Fig. 1; Figs. 3 and 4 are perspective views of the pressed-steel members which constitute the housing of the valve-rotating device on one valve-stem; Fig. 5 is a section on the line 5—5 of Fig. 1; and Fig. 6 is an elevation of the inner or locked-to-stem member of my device.

The two poppet valves 10 and 11 shown in Fig. 1 may be the intake and exhaust valves of one cylinder of the engine, or any two engine valves which are operated simultaneously. As these valves are lifted from their seats 12 and 13 respectively, they open their associated cylinders to valve-chambers 14 and 15 respectively, connected to the usual intake or exhaust manifolds. The valves 10 and 11 have the usual valve-stems 16 and 17, slidably mounted in the engine casting 18 in the usual manner; and

the valves are spring-pressed to their seats 12 and 13 by the usual coiled compression springs 20 and 21 respectively.

Fixed on each valve-stem 16 and 17 is an inner member 25, shown separately in Fig. 6. This inner member 25 is slid onto the valve-stem 16 or 17, but is held fixed thereon by resting on a transverse lock-pin 26 which extends through a transverse hole in the valve-stem and co-operates with opposite notches 27 in a downwardly extending flange 28 at the edge of the bottom of the member 25. The upper end of the inner member 25 is shaped to provide an inner ball-race 29, to receive balls 30; which also co-operate with an outer ball-race 31 formed in the upper end of a pressed-steel sleeve 32 which surrounds the inner member 25. The balls 30 rotatably support the sleeve 32 on the inner member 25. At its lower end, the sleeve 32 has an outwardly projecting flange 33, extended at one point to form an arm having a hemi-spherical half-socket 34 in its upper side (see Fig. 4); and upon the flange 33 rests a pressed-steel ring 35 also provided with an extended arm having a half-socket 36 which mates with the half-socket 34 to provide a substantially spherical socket. The lower end of the spring 20 or 21 bears against the upper face of the ring 35, to hold the ring tight on the flange 33; the thrust of such spring is transmitted through the ring 35 to the flange 33 of the sleeve 32, and from the sleeve 32 through the balls 30 to the inner member 25, and thence through the lock-key 26 to the valve-stem 16 or 17.

The outer surface of the inner member 25 is provided with a plurality of depressions 37, shown as three in number, each deeper at one end than at the other, and preferably wider at their shallower ends than at their deeper ends, as is clear from Figs. 5 and 6. In each of these depressions 37 is a ball 38. The balls 38 tend to roll by gravity toward the shallower and wider ends of the depressions 37. When the sleeve 32 is rotated in one direction, clockwise in Fig. 5, the balls 38 lock the sleeve 32 and inner member 25 together, so that the inner member 25 is carried with the sleeve in such rotation, and in turn rotates correspondingly the valve-stem and valve. When the sleeve 32 is turned in the other direction, or counter-clockwise in Fig. 5, the balls 38 are rolled to the deeper ends of their depressions 37,

to unclutch the inner member 25 from the sleeve 32, so that the valve and valve-stem are not turned. Thus an oscillation of the sleeve 32 about the axis of the valve-stem 5 produces a step-by-step rotation of the inner member 25 and associated valve-stem in one direction, which is clockwise in Fig. 5.

To get this oscillation of the sleeve 32, each sleeve 32 is interconnected with a similar sleeve 32 of another valve, as the sleeves 32 of the valves 10 and 11 are shown interconnected. Any two valves which operate dis-simultaneously may thus be interconnected, whether they are of the same cylinder or of different cylinders of the engine; 15 a convenient interconnection is between the intake and exhaust valves of the same cylinder. The interconnection between the two interconnected sleeves 32 is by a crank-arm 40, which has a ball-headed crank 41 at each end. The balls of the two cranks 41 are located respectively in the spherical sockets (formed by the half-sockets 34 and 36) of the two interconnected sleeves 32. Such sockets 20 of the two associated valves are arranged as shown in Fig. 2, so that when the valves are closed such sockets and the connecting crank-arm 40 are in the horizontal plane (for vertically moving valves), and are on opposite sides of the common vertical plane 25 of the two valve-stems 16 and 17.

When now in the operation of the engine either valve-stem 16 and 17 is lifted, while the other valve-stem remains down, the 30 sleeve 32 on the lifted valve-stem is lifted with it, and this in turn lifts the associated crank 41. The other crank 41, however, remains unlifted, so that as the first crank is lifted it swings about the other crank as 35 an axis, with the necessary ball-and-socket movement of the balls of both cranks, and thus turns the lifted sleeve 32 in one direction about the axis of its associated valve-stem. When the lifted valve returns to its 40 seat, the reverse action takes place, and the sleeve 32 of such lifted valve is rotated in the opposite direction. By reason of the 45 action of the balls 38 and depressions 37, the lifted valve and its valve-stem are rotated 50 on their common axis during one of these 55 rotational movements of its sleeve 32, but not during the other; so that when a valve is lifted and returned to its seat it has been 60 rotated to a different angular position from the one it had before such lifting. This 65 angular movement of the valve with relation to its seat takes place on each complete valve movement (up and down). The sleeve 70 32, however, always returns to the same position after each complete up-and-down movement of the valve, so that there is no 75 tendency to distort or twist the associated valve-seating spring 21.

I claim as my invention:

1. In combination with a poppet valve

and its seating spring, a member fast on the stem of the valve, a second member rotatable on the first member, said seating spring being arranged to act on said second member and through it and the first member on the valve-stem, said two members being provided with means interconnecting them to cause movement of the first member about its axis in one direction upon oscillation of the second member about its axis, and a 70 crank connected between an eccentric point on said second member and a point of support and arranged when the valve-stem is moved longitudinally in opposite directions to cause turning movements of said second member in opposite directions.

2. In combination with a poppet valve and its seating spring, a member fast on the stem of the valve, a second member rotatable on the first member, said two members being provided with means interconnecting them to cause movement of the first member about its axis in one direction upon oscillation of the second member about its axis, and a crank connected between an eccentric point on said second member and a point of support and arranged when the valve-stem is moved longitudinally in opposite directions to cause turning movements of said second member in opposite directions.

3. In combination with a poppet valve and its seating spring, a member fast on the stem of the valve, a second member rotatable on the first member, an anti-friction bearing between said two members, said two members being provided with means interconnecting them to cause movement of the first member about its axis in one direction upon oscillation of the second member about its axis, and a crank connected between an eccentric point on said second member and a point of support and arranged when the valve-stem is moved longitudinally in opposite directions to cause turning movements of said second member in opposite directions.

4. In combination with a poppet valve and its seating spring, a member fast on the stem of the valve, a second member rotatable on the first member, said second member surrounding said first member and said first member being provided with one or more superficial depressions shallower at one circumferential end than at the other, balls in said depressions of suitable size to lock the two members together when in the shallower end of their depressions but to leave them free from each other when in the deeper ends of their depressions, and a crank connected between an eccentric point on said second member and a point of support and arranged when the valve-stem is moved longitudinally in opposite directions to cause turning movements of said second member in opposite directions.

5. In combination, two poppet valves arranged to operate dis-simultaneously, a sleeve on the stem of each of said valves, means interposed between each sleeve and its
5 valve-stem for causing turning of the valve-stem and valve in one direction but not in the other upon oscillation of its associated sleeve, and a crank connecting the sleeves of the two valves to cause the oscillation of each
10 sleeve about its axis as the associated valves are respectively operated.

6. In combination, two poppet valves arranged to operate dis-simultaneously, a sleeve on the stem of each of said valves,
15 means interposed between each sleeve and its

valve-stem for causing turning of the valve-stem and valve in one direction but not in the other upon oscillation of its associated sleeve, and a crank connecting the sleeves of the two valves to cause the oscillation of each
20 sleeve about its axis as the associated valves are respectively operated, and a seating spring for each valve arranged to act on its valve through the sleeve on the stem of said valve.

25

In witness whereof, I have hereunto set my hand at Rock Island, Illinois, this 11th day of July, A. D. one thousand nine hundred and twenty-two.

CHARLES E. SARGENT.
